UNITED STATES PATENT OFFICE.

LUTHER T. PAGE, OF WAREHAM, MASSACHUSETTS, ASSIGNOR, BY MESNE ASSIGNMENTS, OF ONE-HALF TO ROLAND H. BOUTWELL AND ONE-HALF TO ROSWELL M. BOUTWELL, BOTH OF BROOKLINE, MASSACHUSETTS.

METHOD OF MAKING HORSESHOES.

Application filed February 3, 1928. Serial No. 251,646.

The invention to be hereinafter described relates to a method of making horseshoes.

A purpose of the invention is to provide a shoe which will get a good bite or grip on icy, wet and other pavements or surfaces, and a shoe which is strong, simple and durable in construction and can readily be manufactured on a large commercial scale.

With the above and other purposes in view, 10 the character of the invention may be best understood by reference to the following description of the method and the accompanying drawings, wherein—

Fig. 1 is a plan of a horseshoe embodying 15 the invention;

Figs. 2 and 3 are respectively longitudinal and transverse sections through the horseshoe shown in Fig. 1;

Fig. 4 is an elevation of rolls employed in 20 the first two stages in shaping the bar;

Fig. 5 is an elevation of rolls employed in the last two stages in shaping the bar and in marking and finishing the bar;

Fig. 6 on an enlarged scale is a view showing 25 the forms taken by the bar in successive stages in shaping the same;

Figs. 7 and 8 are respectively side and end views of the billet;

Fig. 9 is an end view of the bar drawn out 30 from the billet by the roughing rolls;

Fig. 10 is a plan of the connected pair of bars formed by the rolls;

Fig. 11 is an end view of said bars; and

Fig. 12 on a reduced scale is a plan of a portion 35 of a finished pair of bars.

Referring to the drawings, the horseshoe shown in Figs. 1, 2 and 3 is one good form produced by the method and comprises a body 1, wedge-shaped in transverse cross section from the heels 3 to the toe 5 of the shoe and presenting a fairly sharp tread edge 7 which extends continuously along the heels, quarters and toe of the shoe.

Projecting out from the body is a flange 9 having nail holes 11 therein. The wedge-shaped body has an inner side 15 extending from the top face 17 of the shoe to the tread edge, and an outer side 19 extending from the flange to said edge.

50 In the method of making horseshoes embodying the invention, a suitably heated steel billet 20 (Figs. 7 and 8) is passed through roughing rolls to draw it out into the form of a long bar 20^a (Fig. 9) prefer-

ably square in cross section. These rolls are 55 arranged in a group of three, one above another, and adjacent rolls have opposed grooves therein, being so shaped that as the billet is fed successively in opposite directions between the rolls, it receives four stages 60 of reduction.

This bar is fed while heated between rolls and is shaped in successive stages to final form. To accomplish this, a shaft 21 (Fig. 4) is provided having thereon a roll 23 mating 65 with a circumferential groove 25 in a roll 27 on a shaft 29, said groove being formed so that when the bar is fed between the rolls, it will receive its first stage of shaping and have the form indicated by the dot and dash 70 line *a* (Fig. 6). On said shaft 29 is a roll 31 opposed to a circumferential groove 33 in a roll 35 on a shaft 36, said groove being formed so that when the bar is fed between said rolls, it will receive its second stage of 75 shaping and have the form indicated by the double dot and dash line *b* (Fig. 6).

A marker roll 37 (Fig. 5) is provided on a shaft 39 and is opposed to a circumferential groove 41 on a roll 43 on a shaft 44, said 80 groove being formed so that when the bar is fed between the rolls, it will receive its third stage of shaping and have the form indicated by the triple dot and dash line *c* (Fig. 6).

The groove 41 has punch points 45 thereon for making the depressions 46 (Fig. 12) in the bars for indicating the locations of transverse cuts to be made in dividing the bar into lengths suitable for horseshoes. Also, the groove 41 has punch points 47 thereon for 90 making depressions 48 in the bar to indicate locations of the nail holes.

A finish roll 51 (Fig. 5) on shaft 44 is opposed to a circumferential groove 53 in a roll 55 on a shaft 56, said groove being formed 95 so that when the bar is fed between the rolls it will receive its fourth and final stage of shaping and have the form indicated by the full line *d* (Fig. 6). The finishing rolls will finish the surface of the bar and remove any 100 distortion thereof which may have occurred in the preceding shaping stages.

The bar has now been rolled from its form shown in Fig. 9 to its form shown in Figs. 10 and 11, and comprising two wedge-shaped bodies or bars 1^a, outstanding flanges 9^a and a web 1^b connecting said bodies. The edges or apexes of the bars are opposed to the bases

of the bars. After the bar has cooled the web is sheared longitudinally to separate the two bars. To facilitate the severing operation and insure clean cut edges, a scoring rib 5 51^a may be provided on the roll 51, so that when the connected bars are fed between the finishing rolls, the rib 51^a will score the bar along the web 1^b (Fig. 6).

10 The bars are transferred to a punch machine to make nail holes in the flanges of the bars at locations indicated by the depressions 48 made by the punch points 47 of the marker roll 43. The bars are cut transversely at locations indicated by the depressions 46 made 15 by the punch points 45 of the marker roll 43 to provide pieces of suitable length for forming horseshoes. These pieces are placed in a bending machine to bend them to horseshoe form.

20 It is desirable that a bar shall be used of a size appropriate for production of a pair of connected side-by-side wedge-shaped bars, since this symmetrical shape facilitates feeding of the piece between the rolls and reduces 25 the liability of distortion and reduces strains on the rolls.

A pad 59 of leather, rubber or other suitable material may be employed between the shoe and hoof if desired.

30 There are important advantages in the horse shoe of the present invention. The sharp tread edge of the wedge-shaped body is directed vertically downward and therefore bites into and obtains a good grip on 35 pavements. Since this tread edge is continuous from one heel to the other, it grips pavements throughout its length and resists slip in all directions. Said edge provides a long tread surface, desirably distributes the wear 40 over the whole extent of the edge, and insures

proper position of the horse's hoofs. The shoe is simple and strong in construction and has a pleasing appearance. The shoe is desirable and suitable for both summer and 45 winter use.

It will be understood that the invention is not limited to the specific forms shown, and that various deviations may be made therefrom without departing from the spirit and scope of the appended claims.

50 What is claimed is:

1. A method of making horseshoes having continuous sharp tread edges, characterized by rolling a metal billet to draw it into a bar of substantial length, rolling the bar to shape 55 it into a pair of bars connected by a web and having portions wedge-shaped in transverse section with continuous tread edges and having outstanding flanges, rolling the bars progressively to increase the sharpness of said tread edges and progressively to reduce the thickness of said flanges, and shearing the web longitudinally to separate the bars.

2. A method of making horseshoes having continuous tread edges characterized by rolling a metal billet to draw it into a bar of substantial length, rolling the bar to shape it into a bar having a portion wedge-shaped in transverse section with an outstanding flange, rolling the bar progressively to increase the 70 sharpness of said tread edge, and progressively to reduce the thickness of said flange, rolling the bar to give it throughout its length the final, finished cross-sectional form it is to have in horseshoes, cutting the bar transversely at intervals into lengths suitable for horseshoes, and bending the short lengths into 75 horseshoe shape.
